Atty.

ELIAS BARTO, OF TIFFIN, OHIO.

Letters Patent No. 83,905, dated November 10, 1868.

IMPROVEMENT IN MACHINE FOR MARKING AND COVERING CORN.

The Schedule referred to in these Letters Patent and making part of the same.

To all whom it may concern:

Be it known that I, ELIAS BARTO, of Tiffin, in the county of Seneca, and in the State of Ohio, have invented certain new and useful Improvements in Machine for Marking and Covering Corn; and do hereby declare that the following is a full, clear, and exact description thereof, reference being had to the accompanying drawings, and to the letters of reference marked thereon.

The nature of my invention consists in the construction and general arrangement of a machine adapted both for marking and covering corn.

In order to enable others skilled in the art to make and use my invention, I will now proceed to describe its construction and operation, referring to the annexed drawings, which form a part of this specification, and in which—

Figure 1 is a perspective view of the machine arranged for marking corn-ground, and

Figure 2 shows one of the side arms arranged for covering corn.

A represents a bar, provided at each end with a shaft, *a*, on which the wheels B B are placed.

On the shafts *a*, outside of the wheels, are placed arms C C, which can be moved to any point desired between the wheels and the outer end of the shafts, by means of pins *i i*, placed on each side of the arms, in holes on the shaft, the said shafts passing through a hole in the front ends of the arms.

The arms C C extend a suitable distance to the rear, and are provided at the lower side of their rear ends with a block, D, to the front side of which the shovel-plow E is secured.

The centre of the bar A is rounded, and around this centre part is placed a bent plate or bar, F, open towards the rear, and a similar arm, C, is secured between the ends of said bent bar F by means of a pin, *e*, passing through the same. The front end of this centre arm is grooved out, to correspond with and fit around the rear side of the rounded portion of the bar A. The rear part of the centre arm, C, is also, on its lower side, provided with a block, D, to which the shovel-plow E is secured.

On the bar A are two standards, F F, of suitable height, the upper ends of which standards are forked, as shown in fig. 1, and in these forked ends rest a rod

or bar, G, which is provided with three short arms, H H.

The rear ends of these arms are connected with the rear ends of the arms C C, by means of rods I I, these rods being attached to the arms H H, by a ring at their rear end, and to the arms C C, by a headed pin or screw, in a loop on the ends of said rods, in such a manner that the arms C C can be turned upside down without changing the position of the rods.

A lever, J, is attached to the rod or bar G, at a suitable point to be within reach of the operator, who is seated on the seat K, so that he can at any time, by turning said lever forward and downward, raise the plows E E out of the ground.

On the upper side, and near the rear ends of the arms C C, are cross-bars L L, to the upper side of which are two movable and adjustable blocks, M M.

These blocks can be placed at any distance apart, as may be desired, so that when provided with the spades N N, the corn may be covered, the blocks being, of course, turned in any position required.

To turn the end arms C C upside down, so that the spades N N will come downward, it is only necessary to remove the outside pins, *i i*, when the arms can be taken off the shafts *a a*, turned, and put on again. In like manner, by removing the pin *e*, the centre arm, C, can be removed and turned.

To the front side of the bar A is secured the tongue O, to which the team is attached in any manner desired.

Having thus fully described my invention, What I claim as new, and desire to secure by Letters Patent, is—

The reversible and adjustable arms C C, provided on one side with blocks D and shovel E, and on the other, with cross-bar L, on which are the adjustable blocks M M and spades N N, all constructed and operating substantially as and for the purposes herein set forth.

In testimony that I claim the foregoing, I have hereunto set my hand, this 1st day of August, 1868.

ELIAS BARTO.

Witnesses:

ROBERT LYSLE,
R. ATKINS.
